COMBINED BENCH, EXTENSION TABLE AND CABINET UNIT

Raymond W. Hannah and Kathryn B. Hannah, both of 7200 16th Lane, St. Paul Park, Minn. 55071

Filed Dec. 17, 1969, Ser. No. 20,540

Term of patent 14 years

Int. Cl. D6—01

U.S. Cl. D33—19

FIG. 1

FIG. 4

FIG. 2

FIG. 1 is a view in perspective of a combined bench, extension table and cabinet unit showing our new design.

FIG. 2 is a view thereof in side elevation, as seen generally from right to left of FIG. 1.

FIG. 3 is a view thereof in side elevation, as seen from right to left of FIG. 2 and,

FIG. 4 is a view thereof in side elevation as seen from left to right of FIG. 2.

The side opposite that shown in FIG. 2 and the bottom, neither of which are shown, are devoid of ornamentation.

We claim:

The ornamental design for the combined bench, extension table and cabinet unit as shown and described.
